FISHING FUNNEL

Edward B. Sargent, Mount Lebanon, Pa., assignor,
by mesne assignments, to H. H. Robertson
Company, Pittsburgh, Pa., a corporation

Application June 24, 1932, Serial No. 619,090

15 Claims. (Cl. 247—3)

This invention relates to underfloor wiring conduit systems, and more particularly to apparatus for facilitating the withdrawing of conductors from the hollow sheet metal beams of a metallic base floor.

One object of this invention is to provide a novel and efficient fitting for use with the hollow beams of a metallic base floor for fishing and withdrawing conductors from the beams.

10 A further object is to provide a novel fitting for use in connection with the hollow sheet metal beams of a metallic base floor to aid in the leading of wires or conductors through said beams and through an opening in the beam at a point removed from the place where the wire is introduced into the beam.

15 A still further object is to provide a fitting for use in fishing or withdrawing wires from a conduit or a hollow sheet metal floor beam having a wire deflecting portion and a rounded wire pulling surface.

20 A still further object is to provide a fitting for use in withdrawing conductors or wires from an underfloor conduit or hollow sheet metal beam whereby the wires being led through the conductor or beam will be deflected and led out of the conduit or beam.

25 These and other objects which will herein-after be made readily apparent to those skilled in this particular art are accomplished by means of this invention, one embodiment of which consists in the various structures, arrangements, and combinations of parts hereinafter described and illustrated in the accompanying drawings,

30 wherein:

Figure 1 is a view in longitudinal section of a hollow sheet metal floor beam equipped with one embodiment of my invention;

Fig. 2 is a view in longitudinal section of a hollow sheet metal floor beam showing my improved fitting opening through the bottom of the beams;

Fig. 3 is a sectional view taken on lines III—III of Figure 1;

Fig. 4 is a top plan view of the beam and fitting illustrated in Figure 1;

Fig. 5 is a view in longitudinal section of a hollow sheet metal floor beam provided with a fitting embodying a modification of my invention;

Fig. 6 is a view in longitudinal section of another modification of my invention;

Fig. 7 is a plan view of the beam and fitting illustrated in Figure 6;

Fig. 8 is a plan view of a portion of a hol-

low beam floor embodying a modified form of the invention shown in Figure 6;

Fig. 9 is a perspective view of a hollow sheet metal beam flooring, illustrating apparatus for converting the interior of the beam into an underfloor wiring conduit; and

Fig. 10 is a plan view of a section of a hollow sheet metal beam floor, showing the application of my fitting to the beams to form an underfloor wiring conduit system.

10 In the construction of modern buildings it is becoming more and more common to replace the tile sub-floors in the building with metallic floors which are formed of a series of closely spaced, hollow sheet metal beam sections. These sections 15 of hollow sheet metal beams are supported on the steelwork of the building and are so arranged that the interiors of the beams in one section open into the interiors of the beams of another 20 section and form contiguous passageways which are suitable for use as conduits for the reception of electrical wiring in the building.

25 The present invention contemplates the provision of a fitting which for convenience may be termed a "fishing funnel" for use in facilitating the fishing or withdrawing of electrical wiring or conductors from these hollow beams of the metallic base floor.

30 In the construction of the building the metallic base floor is first erected and then a finish floor, such as concrete or the like, is applied over the surface of the hollow beams. In applying my fishing funnel to the beams I first form an opening in the top of the beams through which the funnel is inserted into the interior of the beam.

35 The funnel itself is connected to a plate which, when the funnel is in place in the beam, forms a cover for the opening cut in the beam and restores the original strength of the beam. The funnel is substantially of L-shape and terminates at one end in a flared-out portion which forms a bell mouth of substantially the same size and shape as the interior of the beam into which it

40 is inserted so that it completely fills the beam and deflects any wires being led therethrough into the body of the funnel. The funnel tapers from the flared out portion and is gradually curved so as to form a rounded pulling surface for the wires or conductors. The other end of the funnel is adapted to project beyond the wall

45 of the beam and may extend through an opening formed in the bottom or side of the beam or in the cover plate. The projecting end of the funnel may extend at right angles to the interior 50 of the beam or in any other suitable direction 55

and may be provided with threads for attaching it to a junction box or to a conduit leading to a suitable junction box.

When my improved funnel has been positioned 5 in a beam intermediate of the end, it is obvious that one end of the beam is "dead" since the flared end of the funnel completely closes the interior of the beam and prevents the wires from being extended the full length thereof.

10 To enable conductors of the electrical wiring system to be inserted into the beam from each end, the fittings may be combined in pairs and arranged so that the flared or bell mouths on the ends thereof inserted into the beams face in 15 opposite directions. This feature of my invention permits the wiring to be fished from opposite ends of the beams or withdrawn from the beam at a point intermediate its ends.

15 Referring now to the drawings in detail, I have 20 illustrated my improved fitting (Fig. 1) as applied to a hollow sheet metal beam 11 of a metallic base floor. While I have illustrated the beam 11 as being formed in two parts and having a lower corrugated V-shaped section 12 and 25 an upper corrugated section 13 which, when superimposed on the lower section, form a series of beams of substantially keystone shape, it is to be understood that my invention may be applied 30 to any type of metallic hollow beam underflooring.

35 After the hollow sheet metal beams 11 forming the base floor have been erected and either before or after the concrete or other finish flooring material is superimposed thereon, the fishing funnels embodying my invention are inserted into 40 preselected beams 11 for facilitating the fishing or withdrawal of electrical wiring therefrom. To install my improved fitting the top of the selected beam 11 is cut away to provide an opening 14 therein for the introduction of the funnel.

45 The funnel comprises a hollow member 15 of substantially L-shape which terminates at one end in a flare or bell mouth 16 of substantially the same shape and size as the interior of the beam 11 in which it is to be inserted so that it 50 will fit snugly therein, engaging the walls of the beam and deflect wires being led therethrough into the member 15. The funnel tapers or converges gradually from the bell mouth 16 and terminates at the opposite end in a cylindrical portion 17 which is adapted to extend beyond the wall of the beam 11. This cylindrical portion 17 of the fitting has a flange 18 formed therearound which supports a plate 19. The plate 55 is secured to the flange 18 through a nut 20 threaded over the end of the cylindrical portion 17. The plate 19 is substantially of channel shape and has legs 21 depending therefrom so that when the funnel has been inserted into 60 the interior of the hollow beam, the plate covers the top and side of the beam 11 and holds the fitting in position in the beam.

65 In order to restore the original strength of the beam 11 the plate 19 may be welded to the top of the beam or secured thereto in any other suitable manner. The threaded end of the cylindrical portion 17 may be attached to a suitable conduit (not shown) for leading the wire fished from the beam 11 to a junction box (not shown) 70 or other source of electrical supply and may extend at right angles to the interior of the beam (Figs. 1 and 3) or the end of the funnel 15 may be bent and internally threaded as in Figure 5, so that it extends parallel to the passageway of 75 the beam 11. This cylindrical end of the fish-

ing funnel may also extend beyond the bottom or side of the beam 11 as well as above the top of the beam, so that an outlet may be formed in the ceiling of the rooms on the floor below the beam, and also to permit the funnel to be connected to a conduit leading to a control switch.

80 In Figure 2 the funnel 15 is shown inverted with the threaded end portion 17 of the fitting 10 extending through an opening formed in the bottom of the beam 11 in order to enable wiring to be drawn outwardly and downwardly from the bottom of the beam to provide a service outlet 15 in the ceiling. In such installations a cover plate 19' is secured to the flared end of the bell mouth 16 and covers the opening 14 formed in the top of the beam 11 and holds the funnel in its proper position in the beam. The funnel is also secured to the beam through a nut 20' threaded over the end of the portion 17 projecting 20 below the bottom of the beam.

When the funnel 15 is installed in a beam 11 intermediate of its length, it is obvious that the wires can be introduced in the beam 11 from only one end since the flared mouth 16 on the beam 25 completely fills the interior of the beam and as a result that part of the beam extending in the opposite direction from the flared mouth of the funnel cannot be used as a conduit. So that conductors can be introduced into both 30 ends of the beam and also so that this wiring may be intercepted intermediate of the length of the beam, the beams may be provided with intercepting fittings (Figures 6, 7, and 8), which are 35 formed by placing two of the fittings in the beam 40 so that the bell mouths thereon face in opposite directions in the beam.

45 As shown in Figure 6, this intercepting fitting 40 comprises a pair of L-shaped deflecting members 25 which are inserted into the interior of the beam through an opening 26 formed in the top thereof. These members 25 are secured to a cover plate 27 which serves to retain the members in place in the beams and also to cover 45 the opening 26.

50 Each of the members 25 is provided with a flaring mouth portion 28 of substantially the same size and shape as the interior of the beam so that they fit snugly therein and engage the walls thereof. Each of the L-shaped members 55 converge from the bell mouth 28 and terminates in a cylindrical portion 29 which extends through an opening in the plate 26 and is threaded as at 30 to receive a suitable conduit (not shown) and lead the wires deflected into 60 the funnels by the bell mouths to a suitable source of electrical supply (not shown). A nut 31 threaded over the end of each of the cylindrical portions 29 of the funnels securely holds the plate 27 against a flange 32 formed on the cylindrical portions 29. The cylindrical ends 29 of the fittings 25 may be positioned longitudinally with relation to the extension of the beam 65 11 in the manner illustrated in Figures 6 and 7, or they may be arranged in transverse relation as shown in Figure 8.

70 The central portion of each of the fittings 15 and 25 is rounded to provide a smooth, curved wire pulling surface to prevent injury to the conductors being fished out of the beams 11. These fittings, either singly or in combination, 75 may also be used to provide, in combination with the beams, a complete underfloor wiring conduit system. In Figs. 9 and 10, I have shown by way of example, how my fishing funnels may be 80

applied to the sheet metal hollow beams 40 of a section of a metallic base floor 41 to form an underfloor wiring system in which the beams themselves form the wiring conduits. These sections 41 which are supported directly on girders 42 of the framework of the building, form the sub-floor of the building and have a layer of finish flooring material superimposed thereon. Preferably, before the finish flooring material is placed over the beams 40, the tops of selected beams desired to be used as conduits, are cut away and my fishing funnel 15 (Fig. 9) is inserted therein.

The end 17 of the funnel projecting beyond the beam is connected to a conduit pipe 43 which leads to a panel box 44 or any other suitable source of electrical supply. While only one beam of the floor section is shown provided with a fishing funnel, it is understood that each or any desired number of beams may be equipped with my funnels. With this arrangement it is possible to secure at any future time, an outlet at any desired place in the floor by merely drilling an opening through the finish floor into the desired beam and then "fishing" feed lines through the opening to the panel box. When the wires are to be inserted into the beams 40 from the panel box 44, the L leading into the interior of the beams may be of substantially the same size and shape throughout its length, and the bell mouth on the end within the beam may be eliminated, since it is only necessary that the wire being fed into the beam be deflected in the proper direction.

While the funnels 15 may be placed in the beams at any desired point along their length, such as at the ends of the beams (Fig. 10), or beneath a partition wall, I prefer to so place them in the beams that the ends thereof will be relatively close to a source of electrical supply. If the funnel is to be placed underneath a partition wall, I prefer to use the double fitting 25 so that the feed wires may be fed into the beam from one end thereof and into one of the funnels 25 and up into the partition where an outlet may be established. After the outlet has been wired, the wires may be led downwardly into the beam through the oppositely disposed funnel. In such cases a single funnel 15 may be placed in the end of the beam so that the feed wires fed into the beam through the funnel 25 may be readily withdrawn from them and led to a source of supply. From the above it is apparent that the several funnels of both the single and double type may be used in combination in each beam.

In practice these fittings may and preferably will be installed in the selected floor beams by first providing an opening in the desired portion of the beam by burning or cutting in any suitable manner. The fitting is introduced into the interior of the beam and the cover plate installed. After assembly, the cover plate may be fastened to the tops and sides of the beam in any suitable manner so that the original strength of the beam will be restored thereto. The fittings embodied in this invention may be formed of sheet metal or by casting, or in any other suitable manner.

While I have illustrated and described my fishing funnel as extending beyond the top and bottom of the beams, it is to be understood that the end of the funnel may be projected beyond the sides of the beams when it is desired to connect the funnel to a conduit disposed between

two of the beams. It is also understood that my improved funnel may be of any desired shape, size, or form without departing from the spirit of my invention or the scope of the appended claims.

What I claim as new and desire to secure by Letters Patent is:

1. The combination with a flooring conduit of a fitting operatively positioned within the conduit for facilitating the withdrawal of the end 10 of an electrical connector through an opening in the conduit, comprising a hollow member having one end enlarged to fit the interior of the floor conduit and form a flaring mouth portion, and a right angle elbow connection to the 15 flaring mouth portion and having its end protruding through an opening in the floor conduit and having provision for enabling it to be connected to another fitting.

2. The combination with a hollow sheet metal 20 floor beam, of a fitting located within said floor beam and comprising a hollow member having one end terminating in a flaring mouth adapted to engage the interior walls of the hollow sheet metal floor beam, and having the other end portion threaded and extended through a wall of an opening in said hollow beam.

3. The combination with a base floor composed of a series of closely spaced hollow beams, 30 of a fitting for facilitating the withdrawal of wiring from the beams, comprising a hollow metal member having a flaring mouth portion positioned in the interior of one of said beams, the marginal portions of said flaring mouth engaging the interior walls of the beam in which 35 it is located, and a second end in communication with the exterior of the said beam.

4. The combination with a base floor composed of a series of closely spaced hollow beams, 40 of a fitting positioned within a selected beam for facilitating the withdrawal of wiring from the beam comprising a hollow metal member having one end flaring and closely fitting the interior walls of the beam, and having the other end projecting through a wall of the beam, said 45 hollow member tapering from its flaring end.

5. The combination with a collaterally arranged hollow beam base floor, of a fitting operatively positioned within a selected beam for facilitating the withdrawal of the end of an electrical connector through an opening in said beam, comprising a hollow member having one end terminating in a bell mouth of a size closely fitting the interior of the floor beam, and having its second end extending at substantially right 50 angles to the direction of extension of the beam, and with the part connecting the ends formed to provide a rounded pulling surface.

6. The combination with a collaterally arranged hollow beam base floor, of a fitting operatively positioned within pre-selected beams for intercepting and for facilitating in the withdrawal of electrical wiring from opposite end portions of the beams, comprising two oppositely faced hollow members, each having one end terminating in a bell mouth of a size closely fitting the interior of the beam and having its second end extending at substantially right 65 angles to the direction of extension of the floor beam, and having the portion intermediate the ends curved to provide a rounded pulling surface.

7. The combination with a metallic base floor having a series of closely spaced hollow beams, of a fitting operatively positioned within selected 75

- beams for intercepting and for facilitating in the withdrawal of electrical wiring from opposite end portions of the beam on each side thereof, comprising two hollow members, each having one end enlarged to fit the interior of the floor cell and form a flaring mouth portion, and a curved hollow conduit connected to each flaring mouth portion and having its end protruding through an opening in the beam and having provision for connection to another fitting.
8. The combination with a wiring conduit of means for facilitating the withdrawal of wiring from opposite ends thereof, comprising a fitting entirely within the conduit and provided with two oppositely faced deflecting members and having ends extended outwardly through a wall of the wiring conduit and into which wiring may be deflected by said deflectors.
9. The combination with a flooring conduit adapted to contain electrical wiring, of two oppositely faced deflectors positioned entirely within the flooring conduit, and two conduits connected with said deflectors within the flooring conduit and extending through a horizontal wall of the flooring conduit.
10. The combination with a flooring conduit, of two hollow deflectors located within the conduit and having flaring mouths facing in opposite directions and having narrower ends projecting through a wall of the conduit.
11. The combination with a flooring conduit provided with an opening in the top thereof, of a cover member for closing the opening and a pair of oppositely faced hollow deflectors secured to the cover member to be inserted into and removed from the conduit and having ends projecting through openings in said cover member.
12. The combination with a metallic base floor formed from a series of closely spaced hollow beams, of a fitting positioned in selected of said beams for facilitating the withdrawal of wires therefrom comprising an L-shaped member having a flared mouth on one end thereof located within the beam, and substantially of the same shape and size as the interior of the beam and a circular portion on the opposite end projecting through a wall of said beam for establishing communication with a conduit pipe.
13. The combination with a sub-floor composed of a series of collateral hollow beams suitable for use as wire conduits, of a fitting positioned within a selected beam for facilitating the withdrawing of conductors therefrom, comprising a hollow L-shaped member having a bell mouth fitting snugly within the interior of the beam and a cylindrical mouth projecting beyond the beam, the central portion of said L being curved to provide a rounded pulling surface for said conductors.
14. The combination with a base floor composed of a series of closely spaced hollow beams, of a fitting for introducing electric feed wires into said hollow beams comprising an L-shaped member located entirely within the hollow beam and having one end disposed in said beam for directing the feed wire in the proper direction and the opposite end projecting out through a wall of said beam and connected to a source of electrical supply.
15. The combination with a flooring conduit, of a hollow fitting provided at its opposite ends with mouths of materially different areas and having intermediate said mouths a curved portion tapering from the larger mouth toward the smaller mouth, the intermediate curved portion and the end having the larger mouth being located entirely within the conduit and the end having the smaller mouth projecting through a wall of the conduit.

EDWARD B. SARGENT.
